UNITED STATES PATENT OFFICE

ALBERT C. KALK, OF CHICAGO, ILLINOIS, ASSIGNOR TO INVINCIBLE LAUNDRY EQUIPMENT COMPANY, A CORPORATION OF ILLINOIS

CONTROL FOR REVERSING MECHANISM

Original application filed August 23, 1926, Serial No. 131,020. Divided and this application filed August 4, 1928. Serial No. 297,419.

This invention relates to a drying machine involving a reversing drive and a manual drive and concerns itself with interlocking mechanism between the reversing drive and 5 manual drive whereby the reversing drive is locked against operation during the operation of the manual drive and vice versa. This application is a division of my copending application Serial No. 131,020, filed 10 August 23, 1926.

The invention comprises the novel structure and combination of parts hereinafter described and more particularly pointed out and defined in the appended claims.

15 In the accompanying drawings which illustrate a preferred form of this invention and in which similar reference numerals refer to similar features in the different views:

Figure 1 is an end elevational view of a 20 drying machine involving this invention;

Figure 2 is an enlarged fragmentary elevational view looking from the right hand side of Figure 1;

Figure 3 is an enlarged sectional view taken 25 upon the line III—III of Figure 1;

Figure 4 is an enlarged sectional view taken upon the line IV—IV of Figure 3 looking in the direction of the arrows, and

Figure 5 is a sectional view upon the line 30 V—V of Figure 3 looking in the direction of the arrows.

In the drawings, there is shown a cylindrical drying machine comprising a cylinder 1, a gear 2 secured coaxially with the cylinder and a pinion 3 for rotating said gear and cylinder. The pinion 3 is secured upon a 35 shaft 4 which is adapted to be driven by suitable reversing mechanism as shown in my copending application.

40 It might be mentioned that the reversing mechanism comprises a shaft 5 (Figure 2) having a slotted slide plate 6 straddling the same. This slide plate has two pairs of studs 7, one pair upon each side of the slot.

45 A wrist pin 8 is located between these studs. The wrist pin 8 is carried by a crank 9 which extends thru said slot and is secured to a shaft 10. Upon the shaft 5 there is secured a triangular shaped neutral plate 11 and the 50 slide plate 6 is provided with spaced plates

12, the lower ends of which form shoulders for coaction with studs 13 secured to the lower corners of the neutral plate 11. Obviously as the slide plate 6 is pulled downwardly by the rotation of the shaft 10 one of the shoulder plates 12 will engage the uppermost pin 13 on the neutral plate 11 and rotate the neutral plate and shaft 5 until the pins 13 are in the same horizontal plane and are engaged by both plates 12. Consequently the 55 downward operation of the slide plate will always bring the shaft 5 to a predetermined position which may be defined as the neutral position in which the cylinder is not rotated. This shaft 5 operates the reversing mechanism and the slide plate 6 controls the operative relation between the shaft 5 and reversing mechanism as shown in my copending case.

The shaft 10 is provided with a bevelled pinion 14 that meshes with a bevelled pinion 15 secured upon a sloping shaft 16 which is journalled in a bearing 17 (Figure 3) upon a shiftable shaft 18. The shaft 16 extends thru said bearing and has affixed thereon an operating crank 19. The shaft 18 is slidably journalled in a suitable bearing having spaced walls 20, 21 and 22. A pinion 23 is secured upon the shaft 18 between the walls 20 and 21; the aforementioned bearing 17 being located between the walls 21 and 22. The pinion 23 is adapted to mesh with the cylinder gear 2 upon proper shifting of the shaft 18 for manually rotating the same thru the instrumentality of a crank 24 upon one end 70 of the shaft 18.

In Figure 3 the pinion 23 is shown in mesh with the cylinder gear 2, and the shaft 16 is now locked from rotation thru the provision of a flat portion 25 thereon which engages the shaft 18. When the shaft 18 is pulled outwardly as shown in dotted lines in Figure 3, the pinion 23 will move out of engagement with the cylinder gear 2, and a groove or concave notch 26 will move under the shaft 16 75 and unlock the same so that it may be rotated.

The shaft 18 is adapted to be retarded by a friction pin 27 having a threaded end engaged by an adjusting nut 28 which abuts the end of the bearing. The friction pin 27 has 80 100

a sloping or bevelled surface 29 for increasing or decreasing the friction upon the shaft 18. When the machine is in operation, the shaft 16 will lie in the concave notch 26 with the flat portion 25 thereof in a position removed from the slot. Consequently shaft 18 will be locked in its inoperative position against longitudinal movement so that the cylinder cannot be manually rotated while the machine is in operation. Now if it is desired to stop the machine, the operator will rotate the crank 19 and actuate shaft 16 and 10 for pulling down the slide plate 6 for throwing out the reversing mechanism and bringing the same to neutral. When this has been done, the flat portion 25 on shaft 16 will have rotated directly over the concave notch or groove 26 unlocking the shaft 18 for shifting movements.

Shaft 18 may now be shifted inwardly for engaging the pinion 23 with the cylinder gear 2. This movement will shift the concave groove 26 beyond the shaft 16 with the result that the flat portion 25 of said shaft 16 will contact the straight top of the shaft 18 and become locked against rotation.

If the cylinder stopped rotating with the door in an improper place for ready access thereto, the crank 24 may be rotated for rotating the cylinder to bring the door to a proper position. Before the machine can be started again, the shaft 18 must be shifted to its inoperative position shown in dotted lines in Figure 3, when the shaft 16 will be unlocked and may be operated for elevating the slide plate 6 and throwing the reversing mechanism in action. When this has been done, the shaft 18 will again become locked by the concave notch 26 for locking the manual drive against operation.

From the foregoing, it will be apparent that a very simple interlocking mechanism has been provided between the reversing mechanism and manual drive whereby only one can be operated at a time, and when one is unlocked for operation the other is locked.

I am aware that many changes may be made and numerous details of construction may be varied through a wide range without departing from the principles of this invention and I, therefore, do not purpose limiting the patent granted hereon otherwise than necessitated by the prior art.

I claim as my invention:

1. In a machine of the class described, a gear, power means for rotating said gear, a shiftable shaft, a pinion thereon for engaging said gear, a bearing on said shaft, a control for the power drive including a rod extending through said bearing, said rod having a flat portion for engaging said shaft for preventing rotation of said rod and said shaft having a notch for receiving said rod when said shaft is shifted to disengage said pinion and gear for the purpose set forth.

2. In a machine of the class described having a reversing mechanism and a rotatable cylinder, power means for rotating said cylinder including a gear, controlling mechanism for said reversing mechanism including a rod, a manual drive for said gear comprising a shiftable shaft and pinion thereon, said rod extending across said shaft, said shaft and rod having recessed parts adapted for coming into operative relation through a shifting movement of said shaft for the purpose set forth.

3. In a machine of the class described, a gear, power means for rotating said gear, a manual drive for said gear including a shiftable shaft, a pinion on said shaft for engaging said gear, a control mechanism for said machine including a manually operated rod crossing said shiftable shaft, said rod and shaft having recessed parts adapted for coming into cooperative relation at predetermined times through the shifting of said shaft.

4. In a machine of the class described, a gear, power means for driving said gear, a manual drive for said gear including a shiftable shaft, a pinion thereon for driving said gear, control mechanism for said machine including a manually operable rod extending across said shaft, said rod having a flat portion for engaging said shaft when said pinion and gear are in meshing relation and said shaft having a notch for receiving said rod when said pinion and gear are in non-meshing relation.

In testimony whereof I have hereunto subscribed my name at Chicago, Cook County, Illinois.

ALBERT C. KALK.
